CLAIM

An ornamental design for a key for releasing a battery pack from an at least partially electric vehicle, as shown and described.

DESCRIPTION

FIG. 1 is a perspective view of an embodiment of a key for releasing a battery pack from an at least partially electric vehicle showing my new design;

FIG. 2 is a right side elevation view thereof;

FIG. 3 is a left side elevation view thereof;

FIG. 4 is a bottom plan view thereof;

FIG. 5 is a top plan view thereof;

FIG. 6 is a front elevation view thereof;

FIG. 7 is a back elevation view thereof;

FIG. 8 is another perspective view thereof, shown in use;

FIG. 9 is another perspective view thereof, shown in further use;

FIG. 10 is a perspective view of another embodiment of a key for releasing a battery pack from an at least partially electric vehicle; showing my new design;

FIG. 11 is a right side elevation view thereof;

FIG. 12 is a left side elevation view thereof;

FIG. 13 is a bottom plan view thereof;

FIG. 14 is a top plan view thereof;

FIG. 15 is a front elevation view thereof;

FIG. 16 is a back elevation view thereof;

FIG. 17 is another perspective view thereof, shown in use; and,

FIG. 18 is another perspective view thereof, shown in further use.

The broken lines showing elements in the above described figures are for illustrative purposes only and form no part of the claimed design.
